PORTABLE COMBINATION CONTAINER AND DISPENSER

Harry E. Barnett, Chicago, Ill.

Application October 31, 1956, Serial No. 619,422

5 Claims. (Cl. 221—266)

This invention relates to dispensers and containers and more particularly to such devices as are adapted for the storage and dispensing of small objects, such as tablets, pills, capsules and the like. Specifically, the invention contemplates a fountain-pen-like structure having means for storing the aforementioned objects therein and means for dispensing or ejecting one or a predetermined number of said objects upon mechanical actuation of the dispenser.

It is well known that a problem has long existed amongst those who of necessity are wont to carry with them medicinal preparations in the form of tablets, pills, capsules or the like; food supplements and substitutes such as vitamins, saccharin, etc., in similar form; or any other objects of similar shape or form having various purposes and functions. The problem experienced by such people relates to the difficulty of properly storing or carrying such objects on the person in sanitary, crush-proof condition.

Attempts to remedy the above-described situation have in most cases proved ineffective. The use of pillboxes or containers, which possibly might protect against excessive breakage or crushing, still did not solve the problem of preventing the admission of foreign matter, including dirt, dust, etc., into the container and thereby contaminating the contents thereof. Furthermore, such conventional containers have been objected to on the grounds that oftentimes it is inconvenient to carry such an object on the person, as for example, in the pocket or in a pocketbook. Moreover, pillboxes are apt to be lost or inadvertently misplaced. Additionally, patients suffering from certain maladies characterized by such symptoms as sudden, unpredictable attacks such as anginal attacks, which require immediate treatment or medicinal dosage, are sometimes unable to select from the box and administer the dosage to themselves in sufficient time to ward off the throes of the attack.

It is therefore a primary object of this invention to provide a medicinal dosage container and dispenser which will overcome all of the disadvantages mentioned hereinabove.

Another important object is to afford a combination container and dispenser which will accommodate pills, tablets, capsules or the like, of various sizes and shapes within certain limits.

A further object is to provide a combination container and dispenser which may be filled directly without necessitating the handling of the medicinal preparations and likewise may be dispensed without requiring direct contact with the hands of the user.

Still another object is to afford a dispenser of the character described having means for visibly determining the condition of the contents thereof and having further means associated with the first-mentioned means for visibly determining the quantity of objects remaining in the dispenser.

Still a further object is to afford a dispenser in which the medicinal preparations may be quickly dispensed with

2

minimum physical exertion, and it is designed to avoid the social embarrassment usually associated with the use of conventional pillboxes.

Yet another object is to provide dispenser and container means for conveniently transporting or carrying objects such as described hereinabove. A related object is to provide such a device with means for insuring against inadvertent loss or misplacement of the dispenser itself.

Yet a further object is to provide a storage receptacle and dispenser which affords maximum protection against crushing or breakage of the contents thereof, and likewise insures against soiling or discoloration of the apparel of the person carrying the objects.

Still a further object is to provide a container and dispenser which insures maximum sanitation in the storage of medications such as may be administered orally. An object relating thereto is to provide a dispenser having means therein for measuring the desired dosage and insuring the mechanical dispensing of the predetermined or measured dosage, thereby eliminating the undesirable practice of returning excessively dispensed tablets to the container.

With the foregoing and other objects in view which will appear as the description proceeds, the invention consists of certain novel features of construction, arrangement and a combination of parts hereinafter fully described, illustrated in the accompanying drawings, and particularly pointed out in the appended claims, it being understood that various changes in the form, proportion, size and minor details of the structure may be made without departing from the spirit or sacrificing any of the advantages of the invention.

For the purpose of facilitating an understanding of my invention, I have illustrated in the accompanying drawings a preferred embodiment thereof, from an inspection of which, when considered in connection with the following description, my invention, its mode of construction, assembly and operation, and many of its advantages should be readily understood and appreciated.

Referring to the drawings in which the same characters of reference are employed to indicate corresponding or similar parts throughout the several figures of the drawings:

Fig. 1 is an elevational view of a combination container and dispenser embodying the principles of my invention;

Fig. 2 is a view similar to Fig. 1 showing the dispenser in a position after rotation through an arc of 90 degrees in a horizontal plane;

Fig. 3 is an enlarged, elevational sectional view of the dispenser in a position similarly to that illustrated in Fig. 1 of the drawings;

Fig. 4 is an enlarged fragmentary sectional view particularly illustrative of the dispensing mechanism, and showing the same in its normal, inoperative or static position;

Fig. 5 is a similar fragmentary sectional view showing the ejecting mechanism in an operative ejecting position;

Fig. 6 is a cross-sectional view taken on the plane of line 6—6 in Fig. 4 of the drawings and viewed in the direction indicated;

Fig. 7 is an enlarged cross-sectional view taken on the plane of line 7—7 in Fig. 3 of the drawings and viewed in the direction indicated; and

Fig. 8 is a perspective detail view of the principal ejector member.

Directing attention first to Figures 1, 2 and 3 of the drawings, it will be noted that reference numeral 10 indicates generally a fountain-pen-like structure embodying the principles of my invention. The structure comprises a tubular barrel 12, with a cap 14 positioned over one end of the barrel and retained thereon by means of complementary screw threads such as 16 formed in the

inner surface of the lower end of the cap 14 and in an intermediate portion 18 of the barrel 12. It will be noted that the cap 14 may be of the usual fountain-pen-cap shape, with an upper conical or dome-shaped portion 20 integrally formed with a uniform-diameter tubular portion 22. At the apex or top of the conical portion 29, a central aperture 22' may be formed, the purpose of which will become apparent as the description proceeds. A spring clip member such as 24 may be affixed to the cap 14 by any suitable means so that the entire dispenser may be readily clipped or attached to a garment pocket or the like in a manner similar to a fountain pen or mechanical pencil.

Turning now to a description of the principal portion of the invention, namely, the barrel 12, it will be noted that the same may comprise a preferably cylindrical member 26 made of any suitable material such as plastic, metal, hard rubber or the like. A pair of elongated hollow passages 28 and 30 are formed in the cylinder 26. The passage 28 extends throughout the length of the cylinder and the passage 30 terminates in spaced relationship with the top of the cylinder, communicating to the side of the cylinder by means of a passage or aperture 32. The function of this aperture 32 will become apparent as the description proceeds.

It will further be noted in Fig. 3 of the drawings that passages 28 and 30 may be separated by a wall 34, the top portion of which is thickened to form an end wall 36 for the passage 30. The wall 34 extends throughout the substantial length of the barrel 12, but terminates as at 38 in spaced relationship with the bottom end of the barrel to afford a cavity 40. The cavity 40 may be closed by a bottom closure member 42 fitted into the bottom of the cylinder as shown in Figs. 3, 4 and 5 of the drawings. It will further be noted that a portion of the cylinder wall 26 is slotted and this slot is then closed by a transparent wall member 44. Again, the function thereof will become apparent as the description proceeds.

The passage 30 may be utilized as a storage magazine within which may be positioned pills or tablets such as P. The pills P are inserted into the magazine through the wall aperture 32, and as will be noted in Figs. 2 and 3 of the drawings, are aligned one above the other in a column with the bottom pill supported on an ejecting mechanism indicated generally by reference numeral 46. This ejecting mechanism 46 will now be described in some detail.

The ejecting mechanism 46 may include an ejector cup 48 pivotally mounted by means of a pivot bolt assembly such as 50 to the wall of the cylinder 26 at the bottom of the pill magazine 30, again as shown in Fig. 3 of the drawings. It will further be noted that the ejector cup 48 is positioned in alignment with a dispensing opening 52 formed in the wall of the cylinder 26 as shown in Figs. 1, 4, 5 and 6 of the drawings. It will be noted that the pivot bolt device 50 is positioned in an opening 52 formed at the midpoint or center of rotation of the dispensing cup 48, thereby insuring free rotation of the cup about its pivotal axis.

The cup 48 may be formed with a crescent-shaped segment 54 affording a semi-annular inner shoulder 56 adjacent a straight back-wall segment 58. The pills P are designed to fit into the open cavity 60 defined by the back wall 58 and the semi-annular shoulder 56 with the bottom of the pill bearing against, or supported by, the surface 56. An opening 62 is formed through the ejector cup 48 in radially-spaced off-center relationship with the center of rotation 52. Rotatably positioned therethrough may be a bolt 64 by means of which the ejector cup is pinned to the bottom end of an actuating bar 66. This actuating bar 66 extends up through the passageway 28 so that the top thereof extends above the top of the barrel 12 as shown in Fig. 3 of the drawings. An ejector button such as 68 may be affixed to the top of the actuating bar 66. This ejector button

protrudes through the opening 22 in the cap 14 and is free to reciprocate therethrough.

It will now be apparent that when the actuating bar 66 is depressed by means of pressure exerted on the top of the button 68, the ejector cup 48 is pivoted or rotated about the central rotation point 50 in the direction indicated by arrows in Figs. 4 and 5 of the drawings. As rotation occurs, the pill P positioned in the cup cavity 60 is moved into alignment with the delivery opening 52 as shown in Fig. 5 of the drawings. Thus, the pill is thereby readily dispensed through the delivery opening 52 while at the same time the outer wall 70 of the ejector cup 48 blocks the dispensing opening 52 thereby preventing more than one pill P from being dispensed at one time. Obviously, if the size of the pills P are small enough or the size of the ejector cup cavity 60 is large enough, more than one pill may be dispensed at one time if so desired. It should also be noted that as the ejector cup 48 is rotated, it jogs the column of pills, thus preventing binding or jamming of the pills in the column above the bottom cavity 40. The arcuate shape of the cup also prevents crushing of the next pill in the column.

In order to insure automatic return of the actuating bar 66 to its normal position for the purpose of readying it for the next dispensing operation, a spring such as 72 is coiled about a lower portion of the actuating bar as shown in Fig. 3 of the drawings. The top of the spring is pinned to the actuating bar by means of a pin such as 74 and the bottom of the spring is anchored or maintained in position by means of a shoulder such as 76 formed in the portion of the cylinder walls 26 and 34 defining the cavity 28. Thus, it will be noted that depression of the actuating bar 66 is accomplished against compression of the spring 72. Hence, when pressure is released from the ejector button 68 the tendency of the spring 72 to expand or return to its normal condition raises the actuating bar back to its normal inoperative position. It will further be noted that as the actuating bar 66 is raised or returned to its normal position, the ejector cup 48 rotates back about its pivot 50 so that the mouth of the dispensing cavity 60 is once more presented upwardly in a position to receive therein another pill P.

It should be noted that the column of pills P in the magazine 30 is fully protected from the admission of extraneous material therein; at the bottom by the dispenser cup 48 and at the top by the cap 14. The wall of the cap 14 closes the filling aperture 32, unblocking the same only for the purpose of refilling the magazine. At such time the cap 14 is unscrewed from the barrel 12, the tablets are inserted in the magazine and the cap is again screwed back on the barrel.

The transparent window 44 permits visual examination of the contents of the magazine 30. If desired, measuring means such as markings 80 may be formed thereon to enable one to judge the amount of pills remaining in the dispenser. Obviously, as a matter of choice the entire barrel 12 could be molded of clear plastic material, but I prefer the construction shown and described hereinabove.

It is believed that my invention, its mode of construction and assembly, and many of its advantages should be readily understood from the foregoing without further description, and it should also be manifest that while a preferred embodiment of the invention has been shown and described for illustrative purposes, the structural details are nevertheless capable of wide variation within the purview of my invention as defined in the appended claims.

What I claim and desire to secure by Letters Patent of the United States is:

1. In a portable dispenser for relatively small objects: a storage magazine having an elongated cavity for storing a column of said objects, the wall of said magazine having a dispensing opening formed near the bottom

thereof in communication with said cavity, a dispensing cup pivotally mounted at the bottom of said cavity and adjacent said dispensing opening, said column of objects supported on said dispensing cup, and means for rotating said cup whereby to eject at least the bottom one of said objects through said opening, said means comprising an actuating bar positioned through said magazine with the upper end thereof protruding above the same, the lower end of said actuating bar pivotally pinned in eccentric relationship to said dispensing cup, said storage magazine comprising a cylinder, said cylinder formed with a second elongated cavity adjacent said storage cavity, said actuating bar positioned in free reciprocating relationship through said second cavity and a portion of the wall of said cylinder adjacent said storage cavity formed of a transparent material for exposing to view the contents thereof, the top portion of said storage cavity formed with a filling aperture through the wall of said cylinder, a tubular cap telescopically mountable over the top of said cylinder whereby the wall of said cap closes said aperture, and means associated with said cap for removably attaching said dispenser to a portion of the clothes of the user thereof.

2. A portable dispenser of the character described comprising a fountain-pen-like device, said device comprising a cylindrical barrel and a tubular cap mounted over the top thereof, said barrel formed with a pair of elongated cavities, both of said cavities communicating with a single enlarged cavity at the bottom thereof, one of said cavities opening to the top of said barrel and the other cavity opening to a top portion of the side of the barrel, a bottom closure member closing the bottom of the barrel, said last-mentioned cavity comprising a pill magazine, said cylinder formed with a dispensing opening in the bottom side-wall thereof, and a dispensing mechanism for ejecting at least one pill from said magazine through said dispensing opening, said dispensing mechanism comprising a dispensing cup positioned at the bottom of said magazine and adjacent said dispensing opening, said cup centrally pivoted to the wall of said magazine, an actuating bar extending through the other cavity and protruding from the top thereof, the bottom end of said bar pivotally connected to said cup

in radially-spaced off-center relationship with the central pivot.

3. The dispenser of claim 2 in which said cap is formed with a central opening in the top thereof, an actuating button mounted on the top of said actuating bar, said button protruding through said central opening, and a spring coiled about a portion of said actuating bar, one end of said spring pinned to said bar and the other end bearing against a shoulder formed in said barrel.
4. In a portable dispenser for relatively small medication objects; a storage magazine having at least a pair of elongated cavities, at least one of said cavities capable of storing therein a column of said objects, the wall of said magazine having a dispensing opening formed near the bottom thereof in communication with said latter-mentioned cavity, a top portion of the wall of said magazine having a filling opening formed therethrough in communication with said latter-mentioned cavity, a dispensing cup pivotally mounted at the bottom of said latter-mentioned cavity and adjacent said dispensing opening, said column of objects supported on said dispensing cup, an actuating bar positioned through said other cavity, said actuating bar operatively associated with said dispensing member whereby said actuating bar may be operated to rotate said dispensing member thereby ejecting at least one of said objects through said dispensing opening, and a closure member mounted on said storage magazine whereby to close said filling opening.
5. The portable dispenser of claim 4 in which said cavities are separated by at least one wall therebetween.
